[57] CLAIM

The ornamental design for a console for van conversion, as shown and described.

DESCRIPTION

FIG. 1 is a bottom, front perspective view of a console for a van conversion showing our new design, it being understood that the broken lines are for illustrative purposes only;

FIG. 2 is a left side elevation view thereof;

FIG. 3 is a right side elevation view thereof;

FIG. 4 is a top plan view thereof;

FIG. 5 is a rear elevation view thereof; and

FIG. 6 is a bottom plan view thereof.
